UNITED STATES PATENT OFFICE.

MICHEL C. HEINEN, OF PRINCETON, MINNESOTA.

STAIR-BUILDING TOOL.

Application filed May 10, 1924. Serial No. 712,209.

To all whom it may concern:

Be it known that I, MICHEL C. HEINEN, a citizen of the United States, residing at Princeton, in the county of Mille Lacs and State of Minnesota, have invented certain new and useful Improvements in Stair-Building Tools, of which the following is a specification.

My invention relates to carpenters' tools and especially to tools used by stairbuilders for laying out the cutting of stringers for stairways.

The object of the invention is to provide an easily regulated and operated guide for drawing the exact lines on a stringer for cutting the same for any size and number of steps and risers desired according to the space available or desirable for a stairway. The invention also involves a new method of doing such layout work.

The means and methods heretofore employed for laying out stair stringers are so crude, slow and unreliable that there is no need of comparing the same to the invention under consideration. Only this may be mentioned, that the regular carpenter's square usually called the steel square is used as a basic element in my device and I use it for setting or adjusting what I will call the primary device of my invention and thereafter a secondary device is regulated or set by the primary device and then the secondary device is ready to be placed upon the stringer as a guide for marking where the saw cuts are to be made for the steps and risers.

In the accompanying drawing:

Fig. 1 is a face or plan view of a steel square with my entire device placed upon it and adjusted for use of a part of it upon a stringer.

Fig. 2 is an enlarged section on the line 2-2 in Fig. 1.

Fig. 3 is an edge view of the bar L looking in the direction of the arrow A in Fig. 4, or in Fig. 4 with the bar turned end for end.

Fig. 4 is a plan view of a stringer with the secondary device placed upon it as a guide for the pencil laying out the cutting for steps and risers.

Fig. 5 is a side elevation of a stringer in position for use after being cut out for the steps and risers.

Fig. 6 is a section on the line 6-6 in Fig. 1 with the secondary device omitted.

Fig. 7 is a metal clamp used in the operation of the device.

Referring to the drawing mainly by reference characters, to avoid confusion with the numbers on the measuring parts, A¹ designates the short arm and A² the long arm of a common square such as used by carpenters who usually call it the steel square. The short arm of it is usually sixteen inches and the long arm twenty-four inches, as shown by the scales A³ and A⁴.

As best shown in Figs. 1 and 6, a metal plate B is firmly secured at C to a straight bar D that is slidably held against and is somewhat thicker than the outer edge of the arm A¹. One edge of the plate is bent to form a guide E over the inner edge of arm A¹ and an extension of said guide forms a spring arm F which at all times presses at the front side of the arm A and causes the friction that holds the plate or clasp thus formed in any desired place on the arm A¹.

Pivoted at G to the outer, upper corner of the clasp is the upper corner of what may be called the primary device in the invention. It consists of a parallelogrammic yoke composed of two long parallel bars H¹, H² and a series of parallel short bars or cleats pivoted at I and bearing numbers say from 8 to 25, or as may be desired, from which the operator may select and use any one according to the number of steps it is found proper for a certain stairway to have. Few if any stairs have less than eight or more than twenty-five steps. The topmost cleat, 26, forms a part of the parallelogram and the cleat 13 is thicker than the adjacent cleats so as to project forward of them and is also extended as 13^x toward the bar D while its other end is the same length as the rest of the step-indicating cleats.

The secondary device consists of a smaller steel square J having near its outer angle a lateral flange K, shown in Fig. 4, and in dotted line in Fig. 1, adapted to guide 100 against the inner edge of the bar D and thereby set the arms J¹ and J² in parallel relation to the arms of the large square A¹-A². The bar 13^x also aids in thus setting the two squares because it contacts 105 with the lower edge of the blade J² and is itself held by the parallelogram parallel to the blade A².

L is an adjustable diagonally disposed straight bar provided with a scale of inches, 110

as are also the arms of the square J. The bar L is preferably made of two parallel members L¹ and L² secured together by screws O near the middle while the end portions are normally slightly spread so as to be drawn together by thumb screws M and N so as to clamp between them the arms of the small square in any adjusted position. Of course, screws M and N may be bolts with thumbnuts if so desired, and the bar members, or at least one of them must have a slot P for the arm J¹ of the square and a slot or groove Q for the other arm. In said groove there may be a rounded point R for the arm J² to guide against, and the arm J¹ is supposed to be in contact with the terminal S of the slot P. At T in Fig. 3 is best shown that the ends of the bars L¹, L² are normally slightly spaced apart. In Figs. 4 and 5 U designates one of the stringers of a stairway to be cut out so as to form faces V to which the risers are to be secured, and faces W upon which to secure the steps. The operation or use of the invention is as follows: Assuming the stairbuilder is to cut out the stringer for a certain stairway; he first places one of the stringers, like plank U in Fig. 4, upon his work bench or other support, and upon the same or upon the bench he places his regular square A¹, A², or such square belonging to the invention as a part of it; places the clasp B—E—F and the parallelogram in about the position shown in Fig. 1. After finding the height X in Fig. 5 to be say seven and one-half feet he moves the clasp with its upper edge to 7½ on the scale A³. He next finds out the available or desirable floor line Y. Taking all obstructions as well as desire for easy rise of steps into consideration, it may be supposed that he finds line Y to be thirteen feet. He then swings the parallelogram on the pivot G and at the other joints I, I, until he gets one of the step indicating cleats with its right hand end as near as he can to the 13 inch mark on square arm A² (every inch there indicating one foot actual floor line 50 the same as every inch on arm A¹ counts for a foot rise) and brings said cleat with its upper edge in line with the lower edge of arm A². If the end of the cleat gets a little beyond 13 or falls a little short of it at the 55 time it is in line with said lower edge the floor line will be correspondingly lengthened or shortened, and if the lengthening is objectionable because of possible obstructions then the remedy is to have one less step by 60 taking the next cleat higher up, say cleat 16 instead of 17 first tried. Under contrary conditions the change may be made as from cleat 17 to cleat 18. When the proper cleat 65 is thus adjusted, the clamp 27 in Fig. 7 is placed as 27 in Fig. 1 and tightened so as

to hold the parallelogram and the large square in the adjusted position.

The operator now places the smaller square J with its arms J² in contact with the upper edge of the forwardly projecting long cleat 13^x which is always parallel to the inner edge of the square-arm A² and the other arm J¹ or its flange K against the bars D and 26 and holds it in that position while he adjusts the diagonal bar L strictly down upon the adjacent corner 26^x of bar 26, and the rest of said bar L into parallel relation to the bar H¹. He then tightens the screws M and N so as to clamp the small square in the bar L. His next step is to pick up the secondary device, the bar L and the small square J and places it upside down upon the stringer as in Fig. 4 and with the diagonal bar against the edge of the plank U and drawing the point of a pencil along the edges of the small square say as S—S²—S³ he gets lines like V—W in Fig. 4, and by moving the secondary device as far as from S to S³ he can mark the successive notches to be cut out in the stringer until he gets as many notches as the number on the step cleat he selected, indicates. After a stringer or two stringers, temporarily stuck together, are laid out as in Fig. 4 and the notches cut, each stringer is turned up with the notched edge up as in Fig. 5 and it will be found to fit correctly from the top of the floor 28 to the under side of floor 29, and counting the said floor 29 for a step the risers (not shown) will be found to be of equal height down the entire stairway.

When another and different stairway is to be laid out the process just described is repeated and the steps may be wide or narrow and the riser likewise by carrying out the adjusting just described with a different height between the floors and a different length of floor line as may be desired or found most convenient.

What I claim is:

1. In a device for laying out stair stringers for cutting, the combination of a main square having its two arms laid out as scales of inches, a clasp frictionally held but slideable upon one of said arms and having a guide bar extending toward the heel of the square, a parallelogrammic device pivoted to the clasp and comprising two normally spaced parallel bars and a series of short parallel cleats pivoted to said bars and bearing numbers indicating various numbers of steps in a stair; means for securing said parallelogrammic device in any desired angular position upon the square, one of said cleats being extra long toward the angle of the square; a smaller square adapted to have one arm resting upon the extra long cleat and the other arm contacting edgewise against the guiding bar of the clasp, and a diagonal bar having means for clamping it

in various adjusted positions upon the arms of the smaller square; said smaller square and diagonal bar being removable from the other parts and applicable upon the stair stringer as a pencil guiding means for marking lines at which to cut notches in the stringer.

2. The structure specified in claim 1, in which the clasp on the main square has a

certain extreme point for the diagonal bar to contact with when in parallel relation to ¹⁰ the long bar of the parallelogram and ready to be clamped to the arms of the small square.

In testimony whereof I affix my signature.

MICHEL C. HEINEN.
